UNITED STATES PATENT OFFICE.

HENRY CREANGE, OF NEW YORK, N. Y.

DESIGN FOR A TUREEN OR SIMILAR ARTICLE.

40,725.

Specification for Design.

Patented June 14, 1910.

Application filed April 16, 1910. Serial No. 555,978. Term of patent 7 years.

To all whom it may concern:

Be it known that I, HENRY CREANGE, a citizen of the United States, residing at New York city, in the county and State of New York, have invented a new, original, and ornamental Design for a Tureen or Similar Article, of which the following is a specification, reference being had to the accompanying drawings, forming part thereof, and in which—

Figure 1 is a top or plan view; Fig. 2 a side elevation, and Fig. 3 an end elevation of a tureen embodying my design.

I claim:

The ornamental design for a tureen or similar article, as shown.

HENRY CREANGE.
